FISHING LURE

James M. Woodley, Maplewood, La.

Application May 8, 1957, Serial No. 46,069

Term of patent 14 years

(Cl. D31—4)

Fig. 1 is a perspective view of a fishing lure showing my new design; and

Fig. 2 is a cross section along the line 2—2 of Fig. 1.

The hook is shown for purposes of illustration. The essential features reside in the portions shown in full lines.

I claim:

The ornamental design for a fishing lure, as shown and described.
